UNITED STATES PATENT OFFICE.

CHARLES SCHOPPET, OF PHILADELPHIA, PENNSYLVANIA.

INTERNAL-COMBUSTION ENGINE.

1,101,042.

Specification of Letters Patent. Patented June 23, 1914.

Application filed November 26, 1912. Serial No. 733,722.

To all whom it may concern:

Be it known that I, CHARLES SCHOPPET, a citizen of the United States, residing at Philadelphia, in the county of Philadelphia and State of Pennsylvania, have invented 5 new and useful Improvements in Internal-Combustion Engines, of which the following is a specification.

This invention relates to internal combustion engines, the object in view being to 10 provide a motor of the rotary or turbine type, embodying a rotor so combined with a reciprocatory piston and mounted therewith on a crank shaft that the gas is compressed by the operation of the reciprocatory 15 piston, and transferred into a combustion chamber, in which it is ignited and then while under expansion admitted to the pockets of the rotor, so as to impart motion thereto.

A further object of the invention is to so 20 arrange the ports and passages of the motor combined with valve mechanism that the direction of rotation of the rotor may be 25 quickly and easily reversed.

With the above and other objects in view, the invention consists in the construction, combination and arrangement of parts, as will be hereinafter more fully described, 30 illustrated in the accompanying drawings, and pointed out in the claim hereunto appended.

In the drawings: Figure 1 is a vertical longitudinal section through an engine, embodying the present invention. Fig. 2 is a vertical section taken at right angles to Fig. 1 on the line 2--2 of Fig. 1. Fig. 3 is a vertical section on the line 3--3 of Fig. 1. Fig. 4 is a horizontal section on the line 40 4--4 of Fig. 1. Fig. 5 is a side elevation of the motor, showing the general arrangement of parts.

In the embodiment of this invention at present in view, I have shown a two-part 45 crank case 1, and an extension at one side thereof and preferably formed integral therewith, and constituting a cylindrical rotor chamber 2, the said case as a whole being divided on the line 3, so as to facilitate the manufacturing and assembling of 50 the engine.

4 designates a cylinder containing the compression chamber 5, in which a reciprocatory piston 6 works, said piston being connected to the crank shaft 7 by means of the 55 usual connecting rod 8.

The piston and cylinder referred to are designed to operate on the two-cycle idea, the piston being provided on its head with a baffle lip 9. The gas is primarily received through the intake pipe 10 connected to a suitable carbureter, and passes inward through the port 11, so that when the piston 6 is in its uppermost position the gas passes directly downward into the compression 60 space 12 of the crank case, and when the piston reaches the lowest point in its stroke the gas under compression is shot upward through a passage 13 and through an inlet port 14 into the compression space 5 above 70 the piston. At the same time, any burnt gases remaining in the compression chamber 5 escape outwardly through an exhaust port 15 and are carried away. In the top of the compression chamber 5, a spark plug 75 16 is inserted for igniting the gas, after it has been compressed a second time by the piston, as the latter reaches the upward limit of its movement.

The rotor 17 is mounted fast on the crank 80 shaft 7, as shown in Fig. 1, and may be provided with one, two or more annular series of gas pockets 18 and 19 separated by vanes as shown, said series being arranged side by side, but separated entirely from each 85 other, 20 designating packing rings to prevent the escape of gas from one series of pockets to another. The engine casing is also provided with an expansion chamber 21 located at one side of the compression chamber 5, and above the rotor chamber 22. The compression and expansion chambers are placed in communication with each other by means of a transfer port 23, embodying a valve seat, against which a resistance or 90 check valve 24 is normally pressed by means of a coiled expansion spring 25 which encircles the stem 26 of the valve 24, and is interposed between a shoulder on the stem and the inner end 27 of an exteriorly threaded 100 stem receiving sleeve or bushing 28 provided at its outer end with a head 29, whereby said bushing or sleeve 28 may be turned in its threaded connection in the frame of the motor, for the purpose of regulating the 105 tension of the spring 25, after the engine has been started. The valve 24 is primarily set to withstand the normal pressure in the compression chamber 5 which usually does not exceed eighty pounds to the square inch. 110 When the gas has been compressed and ignited in the compression chamber 5 by

means of the spark plug 16, the explosion forces open the valve 24 and the expanding gas rushes into the chamber 21.

Between the chamber 21 and the rotor 5 chamber 22 is a gas chest 30 having inlet and exhaust ports 31 and 32 leading downwardly into the rotor chamber, said ports being shown as divergently related to each other and bearing a substantially tangential 10 relation to the periphery of the rotor. These ports alternately serve as inlet and exhaust ports, according to the position of the slide valve 32 which is arranged in the gas chest 30 and capable of 15 being adjusted by means of a valve stem 33 which passes outwardly through a stuffing box in the side wall of the gas chest. The slide valve 32 is shown as provided with a large exhaust space 34, while the gas chest 20 above the rotor is also provided with an exhaust space 35 registering with the space 34. The gas from the chamber 21 is admitted directly into the gas chest, and then passes into one or the other of the ports 31 or 32, which ever is allowed to remain open by the valve 32, the other port then acting as the exhaust.

While the rotor is provided with two or 30 more series of gas pockets 18 and 19, as illustrated in Fig. 1, the slide valve 32 is made in two sections 32' and 32'', and between said sections, reversely extending partitions 36 and 37 are arranged so as to form an intervening exhaust transfer pocket 38. The 35 object of this arrangement is to enable the expanding gases from the chamber 21 to act on the first series of gas pockets 18, and then after passing upward through one of the ports 31 or 32, said gas is transferred 40 through the port 38 to the second series of pockets 19. Exhausting therefrom, the gas passes through a final exhaust passage 39, to which the exhaust pipe 40 is connected.

41 designates an exhaust pipe connected to 45 the exhaust port 15 hereinabove referred to. Both of these exhaust pipes are illustrated in Fig. 4.

Referring now to Fig. 5, the engine as a 50 whole is therein shown in side elevation, 41 designating the exhaust pipe from the cylinder 4. 42 designates the starting crank combined with the crank shaft in the usual manner, 43 a suitable timer or commutator, bevel geared to the crank shaft, and 44 a 55 water circulating pump, the entire casing of the engine being water-jacketed at various points, as shown at 45. 46 designates a transmission gear case, and 47 a coupling

head, by which the shaft may be connected up to any device to be driven, such as the 60 line shaft of an automobile, or the propeller of a motor boat. 29 designates the check valve handle.

The crank case 1 is shown as provided with a drain cock 48, and the casing of the 65 rotor may be correspondingly provided with drain cocks 49 at suitable points.

In Fig. 2, 50 designates one of the brackets which support the shaft actuating the pump and timer, said shaft being shown at 51 in 70 Fig. 5.

From the foregoing description, it will be seen that the gas is first compressed in the crank case 12, then transferred through the passage 13 to the compression chamber 5, 75 and immediately upon being ignited, it escapes past the valve 24 into the expansion chamber 21. While still expanding, it is delivered by the slide valve 32 to one or the other of the ports 31 and 32, and into the 80 pockets of the rotor. The gas after having expanded and filled the first series of pockets 18 is subsequently transferred to the next series 19, and in this connection it may be observed that any desired number of annular 85 series of pockets may be employed, according to the expansive properties of the gas being utilized.

While the engine as a whole is especially designed with reference to use of gasolene 90 gas, it will, of course, be apparent that any expansive gas may be utilized in connection with the construction described.

What is claimed is:

In an internal combustion motor, the combination of a cylinder embodying a combustion chamber, a reciprocatory piston working therein, an expansion chamber arranged at one side of said cylinder and its combustion chamber, a crank shaft to which said piston is connected, a rotor fast on said crank shaft and embodying a plurality of series of vanes, a rotor casing in communication with said combustion chamber, means whereby the gas is transmitted from one 105 series of vanes to the next series, valves for controlling the admission of the expanded gas to each series of vanes, and means for simultaneously shifting said valves to reverse the direction of movement of the rotor. 110

In testimony whereof I affix my signature in presence of two witnesses.

CHARLES SCHOPPET.

Witnesses:

AUGUST WIELAND,
EDWARD WIELAND.
